UNITED STATES PATENT OFFICE.

SAMUEL K. ELLIOTT, OF SAN DIEGO, AND LINNAEUS C. POND, OF LOS ANGELES,
CALIFORNIA; SAID POND ASSIGNOR TO SAID ELLIOTT.

HOSE-NOZZLE.

1,140,259.

Specification of Letters Patent.

Patented May 18, 1915.

Application filed May 4, 1914. Serial No. 836,221.

To all whom it may concern:

Be it known that we, SAMUEL K. ELLIOTT, a citizen of the United States, residing at San Diego, in the county of San Diego, 5 State of California, and LINNAEUS C. POND, a citizen of the United States, residing at Los Angeles, in the county of Los Angeles and State of California, have invented certain new and useful Improvements in Hose- 10 Nozzles; and we do declare the following to be a full, clear, and exact description of the invention, such as will enable others skilled in the art to which it appertains to make and use the same.

15 This invention relates to improvements in hose nozzles.

The object of the invention is to provide a nozzle having simple and efficient means for controlling the configuration of a stream 20 of water flowing through the sprinkler thereof and to provide means whereby a stream may be directed from the nozzle in a fine spray or a tubular stream especially applicable for long distance sprinkling.

25 Another object of the invention is to provide a simple and inexpensive device that may be operated instantly to change the character of the stream without diminishing the volume of water directed from the nozzle 30 and also means whereby the pressure in the hose is immediately relieved after the water is turned off at the hydrant.

With these and other objects in view, the invention consists of certain novel features 35 of construction, and the combination and arrangement of parts as will be more fully described and claimed.

In the accompanying drawings:—Figure 1 represents a side elevation of this improved nozzle; Fig. 2 is a side elevation of the inner tube with the outer tube or casing shown in section; Fig. 3 is a longitudinal section taken on the line 3—3 of Fig. 2; Fig. 4 is an end elevation of the nozzle; Fig. 5 is a transverse section taken on the line 5—5 of Fig. 2; Fig. 6 is a detail perspective view of the spreader; Fig. 7 is a longitudinal section thereof; Fig. 8 is a longitudinal section showing a slightly modified form of the invention; Fig. 9 is an end elevation thereof; Fig. 10 is a transverse section taken on the line 10—10 of Fig. 8; Fig. 11 is a detail perspective view of the modified form of the spreader shown in Fig. 8; and Fig. 12 is a longitudinal section thereof.

In the embodiment illustrated in Figs. 1 to 7 an outer tubular casing 1 is shown having a thickened mouth or discharge end 2 and longitudinally spaced annular ribs 3 and 4 on its outer face near its inner end for a 60 purpose to be described. The inner end of this casing 1 is provided with an annular shoulder 5 on its inner face which is adapted to engage a coöperating shoulder on an inner tube to be described to form a limiting 65 stop for said outer casing.

Slidably mounted in the tube 1 is an inner tube 6 in the outer end of which is secured a collar or sleeve 7 which is welded or otherwise secured to the inner face of said inner 70 casing and the rear edge thereof is adapted to form a shoulder or abutment for a coiled spring to be described. Soldered or otherwise secured to the inner end of the tube 6 is a hose coupling 8 for attaching the nozzle 75 to the hose. This inner tube 6 has an annular shoulder 9 formed on its outer face at a point spaced from its inner end a predetermined distance and which is adapted to be engaged by the internal shoulder 5 of the 80 inner end of the outer casing for limiting the extension of said outer casing relatively to the inner casing and to prevent accidental disengagement of said casings.

The inner tube or casing 6 is provided 85 with a longitudinal depression forming a socket 10 in its outer face in which is mounted an outwardly bowed leaf-spring 11 adapted to frictionally engage the inner face of the outer tube 1 to hold said tube in ad- 90 justed position on said inner tube and prevent the force of the water from changing the position of said tubes accidentally.

The outer end of the collar 7 is preferably beveled or inclined downwardly and inwardly to form a seat to receive the spreading element 12 which is here shown in the form of a truncated cone having a socket 13 at its smaller end in which is mounted a ball or head 14 of a stem 15 whereby a ball and 100 socket connection is provided between said sprinkler head or spreader 12 and said stem 15 whereby said spreader is permitted to adjust itself relatively to its seat and thus produce the most perfect results. This 105 spreader has a slot 16 extending longitudinally therethrough which is designed for relieving the pressure of the water in the hose between the hydrant and the spreader after the water has been turned off. The rear end 110

of the stem 15 is enlarged to form a stop or shoulder 15' adjacent said end, which shoulder is designed to form a stop or abutment for one end of a coiled spring 17 which encircles said stem and bears at its other end against the inner edge of the collar 7. A spiral spring is here shown with its smaller end engaging the abutment formed by the shoulder of the enlargement and its larger end engaging the inner edge of the collar 7.

It will be obvious from the above description that the water under pressure passing through the nozzle will force the spreader 12 outwardly against the tension of the spring 17 thereby compressing said spring between the stop 15' and the collar 7 thus opening the nozzle and permitting water to pass out between said spreader and the seat formed on the collar 7. It will be noted that all water discharged from the nozzle, must necessarily flow first through the spaces between the various convolutions of the cone-shaped spring 17, and that these convolutions are moved toward each other as the spreader is forced outwardly by the pressure of the water. This is extremely advantageous, since should the water pressure be so great as to force the spreader too far from its seat, thereby allowing a stream of undesirable pressure to be furnished, the amount of water flowing through the spring is automatically diminished, since the spaces between the convolutions of said spring are decreased in size, as the spring is compressed. On the other hand, when the pressure is normal, the spreader will be so positioned as to allow the spring to serve to permit the proper amount of water to flow through the device. As soon as the water is cut off, this spring 17 will again expand thereby retracting the spreader 12 and seating it on the collar 7 closing the nozzle. This backward movement of the spreader 12 under the action of the spring 17 will slightly compress the water in the hose between the hydrant where it has been cut off and the sprinkler and this pressure may be relieved by means of the slot 16 which extends longitudinally through the spreader and permits the water to pass out therethrough and drain the hose.

The inner and outer tubes 1 and 6 are here shown substantially of the same length but they may be of different lengths if desired and the outer tube is slidable on the inner tube for the purpose of varying and controlling the configuration of the stream of water issuing from the nozzle. For instance, when the outer tube 1 is projected to its full extent as shown in Fig. 2, the spreader head will be positioned some distance within said tube so that when the water is admitted to the hose and forces said spreader open, the walls of the outer tube which extend beyond

said spreader head will confine the stream of water and direct it in a tubular stream from the hose. The force and size of the stream may be varied by lengthening or shortening the distance between the outer end or mouth of the tube 1 and the spreader 12 of the other end of the inner tube 6. When the outer ends of the inner and outer tubes are disposed flush with each other, the force of the water passing out will open the spreader and the water will be discharged in the form of a fine spray spreading out in all directions.

The annular ribs 3 and 4 which are preferably roughened or knurled are designed to receive the thumb of the operator between them so that the outer sleeve may be moved backwardly or forwardly with one hand for varying the size of the stream ejected.

From the above description it will be obvious that the character of the stream may be quickly changed with one hand without diminishing the volume of water directed from the nozzle.

In the form shown in Figs. 8 to 12 the inner and outer tubes 1 and 6 are similarly constructed to those shown in the other figures the difference residing in the formation of the spreader or head 12' and in the means carried by the stem 15 between which and the ring 7', the coiled spring 17 is mounted. This spreader 12', the outer end of which is reamed out to form a cup-like head, has two small holes 16' drilled at an angle through said spreader and which are designed for the same purpose as the slot 16 in the spreader 12, that is to relieve the pressure in the hose after the water has been cut off at the hydrant.

A spider 19 is fixed to the inner end of the stem 15' and is slidable within the inner tube 6 forming a guide for said stem and the spreader connected therewith.

The operation in this form of nozzle is exactly the same as that above described and consequently, no further description is thought to be necessary.

What we claim as new is:—

1. A nozzle comprising a tube having an annular seat in its outer end, a spreader engaged with said seat and adapted to move outwardly therefrom, a stem extending inwardly from the spreader into the tube, a stop on the inner end of said stem, and a conical spring whose contracted end encircles said stem and bears against the same and against said stop, its expanded end bearing against the inner end of the annular seat, whereby water forced through the tube must pass between the convolutions of the spring, and whereby said convolutions will be forced toward each other when the spreader is moved excessively outward thereby decreasing the amount of water discharged from the nozzle.

2. A hose nozzle comprising a tube having a spreader seat at its outer end, a spreader engaged with said seat and adapted to move outwardly therefrom, and a conical coiled 5 spring disposed within the tube and through the convolutions of which water discharged therefrom must pass, said spring exercising its tension to retain the spreader in engagement with its seat, whereby excessive outward movement of the spreader will compress the spring and check the discharge of 10 water therethrough.

In testimony whereof we have hereunto set our hands in presence of two subscribing witnesses.
